UNITED STATES PATENT OFFICE.

MORRIS LEON AND ALPHA B. VANCE, OF FORT SMITH, ARKANSAS; SAID VANCE
ASSIGNOR TO SAID LEON.

DISPLAY-HOLDER.

1,273,239.

Specification of Letters Patent. Patented July 23, 1918.

Application filed September 14, 1916. Serial No. 120,148.

To all whom it may concern:

Be it known that we, MORRIS LEON and ALPHA B. VANCE, citizens of the United States, residing at Fort Smith, in the county of Sebastian and State of Arkansas, have invented certain new and useful Improvements in Display-Holders, of which the following is a specification, reference being had therein to the accompanying drawing.

10 This invention has reference to those display devices that are known as "T-stands", which ordinarily include a base, an upright standard, and a substantially horizontal bar or cross-piece at the top of the standard over 15 which articles of fabric may be draped.

The present invention has particular reference to a holder for supporting more rigid articles such as shoes, boxes, etc., on or independently of such stands, a holder of 20 this general nature being disclosed by our co-pending application for Letters Patent on improvements in display-holders, filed March 11, 1916, Ser. No. 83,524.

It is an object of this invention so to form 25 a holder that it may be placed in any desired position on the upright standard without removing the cross-piece or other parts of the stand, and be adjusted to and reliably held in different places thereon.

30 Further, the holder is adapted to support canes, umbrellas, and other similar articles, as well as shoes, boxes, etc. Moreover, it is susceptible of use independently of a stand.

When read in connection with the description herein, the details of construction and arrangement of parts contemplated by the invention will be apparent from the accompanying drawing, forming part hereof, wherein an embodiment of the invention is 35 disclosed, for purposes of illustration.

Like reference characters refer to corresponding parts in the views of the drawing, of which—

Figure 1 is a front view of the holder on a 40 stand;

Fig. 2 is a side view thereof;

Fig. 3 is a plan view of the holder; and

Fig. 4 is a view of the holder in use independently of a stand.

Having more particular reference to the drawing, A designates a base, B a standard, and C a cross-piece of a T-stand such as commonly is used for display purposes in stores

and elsewhere for display of fabric articles that may be draped over the cross-piece. 55

It frequently is desired to display, in connection with articles that can be draped, others that, because of their character cannot be draped or otherwise conveniently be attached to a T-stand of ordinary form, such, 60 for example, as hosiery and shoes, which often are sold together and sometimes are required to match in color, and this invention is designed to meet this demand in a simple and practical manner. 65

For this purpose, the invention provides a holder that includes a platform 5, which preferably is made of bendable sheet metal, but also may be made of wood or other suitable material. The platform has at its normal lower end a flange 6, which may be formed by bending when pliable material is used for the platform, this flange being for the purpose of retaining articles on the platform when it is in an inclined position, as it 70 ordinarily is when in use. The platform in its upper portion has on each side a hook or other projection 7 adapted to engage a substantially horizontal member such as the cross-piece C of a T-stand, and when the 75 platform is made of pliable material the hooks or projections may be formed by slitting and bending the material.

Near the portion of the platform that is normally the lower there is hinged on the 80 back thereof an arm 8, having at its free end an indentation or seat 9 arranged to engage an upright member such as a standard B of a T-stand, so that, when the hooks or projections 7 are in engagement with the cross-piece, the arm will act as a strut to maintain 85 the platform at an inclination.

In order to keep the arm 8 outstanding from the back of the platform, so that it is in position for engagement with a standard or the like, and to keep it from swinging against the platform when the device is used independently of a stand or similar support, a strut 10 is hinged at or near the free end of the arm and is arranged to contact at its free end with the under surface of the platform at a place removed from the connection of the arm and platform, and the free end of the strut may be held in engagement with the platform by a hook or 100 other projection 11, which may be formed by 105

bending out of the material of the platform when the material is pliable. The hinged connections of the arm with the platform and strut permit those parts to be folded against 5 the platform when desired.

For the purpose of permitting the platform to be supported on a standard or other similar upright independently of a cross-piece at any desired position, the platform is formed, preferably in its normal 10 upper portion, with an opening 12, somewhat larger than and arranged to permit the upright to project therethrough. The opening being larger than the upright, the 15 platform may assume an inclined position with respect thereto. The edge of the opening at two places engages the upright, and by such frictional contact the platform is prevented from sliding downwardly on the 20 upright. Of course, the platform may be adjusted to different heights on the upright by moving it after it is brought to substantially right angles with respect thereto whereby the clamping action of the edge of 25 the opening is released. In order to increase the reliability of the hold of the platform on the supporting upright, the edge of the opening 12 at one of the places where it engages the upright is formed with projections 30 or teeth 13. In the present embodiment, the projections or teeth are formed by enlarging the upper side of the opening by cutting away the edge on intersecting arcs, as shown at 14, the teeth or projections being at the 35 places of intersection of the arcs with one another and with the contour line of the opening proper.

In order that the platform may be brought to and removed from association with an 40 upright extending through its opening 12 without the necessity of passing the platform over the top of the upright, a slot 45 15, of a size to accommodate the upright, extends from the edge of the platform to the opening. Thus, when it is desired to place the platform on the upright, it is

brought to substantially right angles thereto and the upright is passed through the slot to the opening, when the platform assumes an inclined position with respect to the upright and the edges of the opening engage therewith. The slot, therefore, permits the platform to be placed on the standard of a T-stand without removing the cross-piece at the top and also on one that has projections 50 that are impossible or impracticable of removal. In the particular embodiment shown the lower edge of the slot extends from one of the hooks 7. The slot 15 may be used not only for the passage of the upright into and 55 cut of the opening 12, but also to accommodate a cane, umbrella, or the like, in which case such an article, if necessary to maintain it on the holder, may be made to engage the hook 7 below the slot. 60

When the platform is supported by engagement of the edge of its opening with an upright, the arm 8 and strut 10 may be folded against its bottom, if desired, or they may be left in extended position. Moreover, 70 the arm 8 by engagement of its seat 9 with the upright below the opening may coöperate in the maintenance of the platform in proper position when the upright extends through the opening, if that is found desirable. 75

Having thus described our invention, what we claim as new, and desire to secure by Letters Patent, is—

A display-holder comprising a platform having in its upper portion an opening 85 adapted to accommodate a standard, an arm hinged to the lower portion of the platform and arranged to engage the standard below the opening in the platform, and a strut hinged to said arm at a place removed from 90 the place of connection of the arm and platform and arranged to engage the upper portion of the platform.

In witness whereof, we affix our signatures.

MORRIS LEON.
ALPHA B. VANCE.
